(57) **CLAIM**

The ornamental design for a nerve conduction assessment device, as shown and described.

DESCRIPTION

FIG. 1 is a left perspective view of the top of the nerve conduction assessment device;

FIG. 2 is a top right perspective view thereof;

FIG. 3 is a bottom left perspective view thereof;

FIG. 4 is a bottom right perspective view thereof;

FIG. 5 is a top view thereof;

FIG. 6 is a bottom view thereof;

FIG. 7 is a right side elevational view thereof;

FIG. 8 is a left side elevational view thereof;

FIG. 9 is a front elevational view thereof; and,

FIG. 10 is a rear elevational view thereof.

1 Claim, 10 Drawing Sheets
